His Attorney.

UNITED STATES PATENT OFFICE.

FRANK A. BENFORD, OF SCHENECTADY, NEW YORK, ASSIGNOR TO GENERAL ELECTRIC COMPANY, A CORPORATION OF NEW YORK.

SEARCHLIGHT WINDOW.

1,404,004.

Specification of Letters Patent. Patented Jan. 17, 1922.

Application filed January 7, 1921. Serial No. 435,722.

To all whom it may concern:

Be it known that I, FRANK A. BENFORD, a citizen of the United States, residing at Schenectady, in the county of Schenectady, 5 State of New York, have invented certain new and useful Improvements in Searchlight Windows, of which the following is a specification.

My invention relates to searchlight windows through which the rays of light which are projected from a parabolic mirror or other optical system parallel to the axis of the mirror or system shall pass into the field of illumination as a beam of parallel 10 rays. Searchlight windows of this general character have heretofore been made of one pane of plane glass, through which parallel rays pass and issue from the same as a parallel beam; but it was found that such 15 window, even if made of considerable thickness, is liable to crack and break by reason of the high temperature and great variations of temperature to which it is subjected, and more particularly by reason of the sudden and violent gas pressures against its outer surface due to artillery fire in its immediate vicinity, when the searchlight is used in warfare. To overcome this serious 20 defect, the plane glass window was built up 25 of strips placed edge to edge. These strips, however, would not sufficiently close the searchlight casing against the entrance of rain or spray, to the detriment of the source 30 of light. Moreover, the glass strips are also liable to breakage, although in a less degree, 35 by gas pressure from the outside. In addition thereto, the dull ground edges of the strips intercepted a considerable percentage 40 of light.

It has been attempted of late to overcome these difficulties by employing concavo-convex windows with the convex side on the outside, and these windows actually secured 45 a good closure against the entrance of rain and spray and were safe against breakage; but by reason of the particular curvatures given to these concavo-convex windows, as will appear further on, the parallel rays which they receive from the optical system 50 are by refraction largely diverted outwardly, so that the benefit of a parallel beam is to this extent lost. This parallax of refraction is barely noticeable near the center of

the window, but becomes serious at all points remote from the center.

55

The object of my invention is to produce a concavo-convex searchlight window in which the parallax of refraction is reduced to zero or to a negligible minimum, and I accomplish this result by giving to the two 60 surfaces of the window such relative curvatures, depending upon the specific index of refraction of the glass employed, that the two surfaces are practically parallel within the range of incident and outgoing rays and 65 therefore cause the parallel rays of light received, to issue as a practically parallel beam.

In order to fully appreciate the beneficial 70 effects of my invention and the departure of the invention from the prior art, a brief review of the latter becomes necessary, and for this reason the accompanying drawings which constitute a part of this specification display, in addition to the invention also two 75 constructions of searchlight windows, which have heretofore been used and which have been found wanting. Fig. 1 represents a section of a parabolic searchlight window heretofore used, with the course of a ray of 80 light through the same indicated; Fig. 2 is a like view of a concentric spherical searchlight window heretofore used, and Fig. 3 is a like view of my improved searchlight 85 window.

In these drawings the thicknesses of the window glasses are somewhat exaggerated in order to trace the course of rays of light through the same with greater comfort; in consequence the angles of divergence necessarily also become exaggerated, but with the assumption of a thicker glass everything is drawn to scale. The dimensions here under consideration are necessarily small and the partly exaggerated scale is, therefore, just 90ified.

In Fig. 1, the window glass 10 has a concave inner surface 11 accurately ground to a true paraboloid, while the outer convex surface deviates from the parabolic form in 100 such manner that if this glass is used as a reflector, with the silvering on the convex face, rays from the focus of the inner face will, after refraction and reflection and repeated refraction, issue from the concave 105 face as a beam of parallel rays. Such para-

bolic mirrors are spoken of in the art as mirrors "corrected for refraction" and they serve their purpose fairly well. Such pieces of glass, but with the silvering removed, 5 have heretofore been used as searchlight mirrors, and Fig. 1 represents a window glass of such description. It will be noticed that this glass is thicker at the edges than at the center. The normal to a point g_1 near 10 the edge of the inner face is designated by R_1 and for the outer face at g_2 , by R_2 and these normals intersect the axis at C_1 and C_2 respectively. The axis X of the inner face parabola is understood to coincide with the 15 axis of the optical system from which the window receives parallel rays. In the example shown in the drawing R_1 makes an angle a_1 of 30° and R_2 an angle c of 22° with the axis. One parallel ray L_1 is indicated in 20 the drawing. It strikes the window at or near the edge at the point g_1 at the angle a_1 (30°) to the normal R_1 . The index of refraction m of ordinary glass with reference to air is about 1.52, and the ray L_1 enters 25 the window at an angle b_1 to the normal R_1 , being turned from its original course toward the normal, which, as shown in the drawing, is a clockwise diversion; the refracted ray within the glass is marked by the 30 letter L_2 . This refracted ray strikes the convex face of the window at g_2 and there makes with the normal R_2 an angle a_2 ; it is there again refracted but since in this case 35 the index of refraction of air with reference to glass is $\frac{1}{m}$, the refraction is away from the normal R_2 , that is to say, it is counter-clockwise, the ray issuing in the direction L_3 , making with the normal an angle a_2 . The 40 angle of refraction a_2 is smaller than the angle of refraction b_1 , so that the issuing ray L_3 still forms a clockwise angle with the axis of the parabola; this angle is, therefore, an outwardly divergent angle. The 45 absolute value of this angle of divergence is small, much smaller than shown in the drawing, but its practical value is considerable, because it diverts from the central beam a considerable amount of light into the circumference of the beam and thus reduces 50 the central intensity.

In a $36''$ searchlight using a window as above described accurate calculations showed a maximum divergence each way outward 55 from the axis to be $0^\circ, 16', 25, 25''$, so that the actual spread was $0^\circ, 32', 50, 50''$, which is quite a serious matter.

Referring to Fig. 2, the window glass 10 is 60 of the spherical type, heretofore used, the two surfaces being accurately concentric; they have a common center of curvature C_1 , and all lines and angles are marked with the same letters of reference as the corresponding parts in Fig. 1. The course of a ray of 65 light through this window can therefore, be

easily traced. The angle of outward divergence of the ray L_3 is, as in Fig. 1, the angle formed by that ray with a line parallel to the axis. The angle of divergence in this case is smaller than in the case of the parabolic window; it has been accurately calculated in a $36''$ searchlight at a point near the edge and was found to have there a total spread of $0^\circ, 23', 14, 22''$, which is still quite 70 a serious matter. 75

It will now be understood that the outward divergence of parallel rays of light directed against the concave surface of windows heretofore used is due to the fact that the normals to the points of incidence and exit for each ray form an angle. The greater this angle the greater must be the divergence, and in fact the divergence is very nearly equal to one-half the angle between the normals. In accordance with my invention the 85 angle between normals to a pair of points of incidence and exit, respectively, is made practically zero and consequently there is no divergence. Of course, the concave and convex surfaces cannot, as a whole, be parallel, 90 but to each element of the concave surface at the point of incidence of a parallel ray corresponds an element of the convex surface at the point of exit, and by my invention these conjugated elements are made practically 95 parallel, and by reference to Fig. 3 the construction by which this is accomplished is explained.

In Fig. 3 the concave surface of the window 10 is accurately spherical, the center 100 of curvature being at C_1 , and the suitably chosen radius of curvature is R_1 . The convex surface is also accurately spherical, but its center of curvature C_2 , is a certain distance D nearer the inner surface, and in 105 this respect the construction differs from those heretofore used and shown in Figs. 1 and 2. The as yet undetermined radius of curvature of the convex face is R_2 . By reason of this construction the new window 110 is thinner at the edge than in the center; the difference in thickness is small but it is significant, and in order to make this difference apparent to the unaided eye the window glass lines have in the drawing been extended beyond the edge of the window. The 115 thickness of the edge as measured along the radius R_2 , is denoted by T_a , and this thickness can be chosen at will and is therefore a constant upon which, together with the index of refraction and the arbitrary length of R_1 , the values of D and R_2 depend. These

are the two critical quantities; when a rule for ascertaining these quantities has been established a window in accordance with my invention can be constructed. This rule is arrived at by the following considerations. 120

Let the index of refraction (from air into glass) be m , the angle of incidence of a 125 parallel ray L_1 at the point g_1 , be denoted a , 130

and the angle of refraction of that ray in the glass be denoted b ; then we have

$$\frac{\sin a}{\sin b} = m.$$

5

The distance S from the normal R_1 , at which the ray (being now L_2) emerges at g_2 is approximately

$$10 \quad S = T_a \tan b.$$

In order that the elements at g_1 and g_2 be parallel, the normal R_2 to g_2 must be parallel to R_1 , and when it is thus drawn it intersects the axis X at the point C_2 . Consequently

15

$$D = \frac{S}{\sin a}$$

$$= T_a \frac{\sin b}{\sin a \cos b}$$

$$20 \quad = \frac{T_a}{m \cos b}.$$

The length of R_2 (the radius of curvature of the convex surface) is

$$25 \quad R_2 = R_1 + T_a - D \cos a.$$

If in this equation the value of D determined above is substituted R_2 is found to be

$$30 \quad R_2 = R_1 + T_a - T_a \frac{\cos a}{m \cos b},$$

or

$$35 \quad = R_1 + T_a \left(1 - \frac{\cos a}{m \cos b} \right).$$

The quantities D and R_2 being thus determined under the condition of parallelism of the conjugated elements g_1 and g_2 , it follows of necessity that the issuing ray L_3 40 is parallel to the incident parallel ray L_1 ; its divergence is therefore zero, and a parallel beam striking the concave surface of the window at g_1 issues at the convex surface as a parallel beam.

45 In the searchlight windows heretofore used the divergence of the issuing rays from parallelism is greatest at and near the edge of the window and decreases toward the center. At the center itself there is no divergence and for some distance from the center the divergence does not become practically appreciable. By my invention, the divergence of rays at the edge is entirely abolished and for some distance from the 50 edge the divergence does not become practically appreciable. Therefore, in the new searchlight window there is one zero point of divergence (in the center of the window) and one zone of zero divergence (at the edge) 55 and while in the intermediate space there is, theoretically some divergence of issuing rays, this divergence is as a whole practically not appreciable. The new window, therefore, renders the issuing rays practically parallel.

Since both surfaces of the window are truly spherical, they can be easily ground to scale when the rules for determining the quantities D and R_2 above stated are observed. Moreover, for the guidance of the manufacturer of this searchlight window and as a test of the accuracy of the construction, the thickness of the central part of the window in terms of the index of refraction and of the arbitrarily chosen thickness at the edge can be calculated from the above formulae. This, however, is a matter within the knowledge of a person skilled in the art and is therefore not dwelt upon.

Accurate tests of the light flux obtained with a 36" searchlight have shown that with the use of a window of my invention the intensity of light projected into the central portion of the beam is about 18% greater than with a parabolic window such as heretofore described.

It is self-evident that my improved searchlight window is reversible, that is to say, the concave side of it may be placed outwardly, so that the parallel rays from the reflector 90 or other optical system may be received at the convex face and will then issue as a parallel beam at the concave face.

Having now fully described my invention, I claim and desire to secure by Letters 95 Patent:

1. A searchlight window comprising a concavo-convex plate of glass having eccentric spheroidal surfaces related to each other to make the parallax of refraction for 100 rays of light parallel to the axis substantially zero.

2. A searchlight window comprising a concavo-convex plate of glass having eccentric spheroidal surfaces, their eccentricity, 105 radii of curvature and thickness of glass near the edge being related to make the parallax of refraction for rays of light that are parallel to the axis substantially zero.

3. A searchlight window comprising a concavo-convex glass having on its opposed surfaces a pair of conjugated substantially parallel elements for each ray of light parallel to the axis incident upon either one 115 of the surfaces.

4. A searchlight window comprising a concavo-convex glass having opposed eccentric spheroidal surfaces, each surface having an element that is substantially parallel 120 to a corresponding element on the other surface for each incident ray that is parallel to the axis.

5. A searchlight window comprising a concavo-convex plate of glass having opposed eccentric spherical surfaces, so related that the normal to any point of incidence of a ray of light substantially parallel to the axis is parallel to the normal at 125 the point of emergence.

130

6. A searchlight window comprising a concavo-convex plate of glass having opposed eccentric spherical surfaces, so related that the normal to any point of incidence at the edge of the plate of a ray of light parallel to the axis is parallel to the normal at the point of emergence and the

normal to any point of incidence between the edge and center is substantially parallel to the corresponding point of emergence. 10

In witness whereof, I have hereunto set my hand this 6th day of January, 1921.

FRANK A. BENFORD.
